UNITED STATES PATENT OFFICE.

MARY E. HOYLE, OF CHICAGO, ILLINOIS.

LADY'S HAND-BAG.

SPECIFICATION forming part of Letters Patent No. 518,034, dated April 10, 1894.

Application filed November 2, 1893. Serial No. 489,852. (No model.)

To all whom it may concern:

Be it known that I, MARY E. HOYLE, a citizen of the United States, residing at Chicago, in the county of Cook and State of Illinois, 5 have invented a new and useful Improvement in Ladies' Hand-Bags, of which the following is a specification.

My invention relates to an improvement in the class of bags commonly carried in the 10 hand by ladies while on shopping or other expeditions as a convenient storage-receptacle for small articles.

The primary object of my improvement is to provide a construction of bag, in the class 15 referred to, whereby it shall afford, in addition to the handkerchief-pocket and general pocket usually provided in such bags, at least one additional compartment adapted to hold, and which is equipped with means for remov- 20 ably retaining, a book, particularly a memorandum or other book, and preferably both.

My further object is to provide the bag with additional pockets or compartments arranged in a manner to render it compact and 25 avoid bulkiness, one such compartment being especially designed for holding and hiding from view a lunch-box; another being of a secret nature, formed in the aforesaid general compartment with a taut partition re- 30 sembling lining; and other collapsible pockets, one, say, for letters, and another for cards being provided in the book-holding compartment.

Referring to the accompanying drawings— 35 Figure 1 is a perspective view of my improved bag showing it open to display the general and secret pockets and also the compartment containing the books and lunch-box. Fig. 2 is a cross-sectional view of the same. Fig. 3 40 is a perspective view like that shown in Fig. 1, but presenting the interior of the book-compartment, from which the lunch-box is omitted, and the minor pockets on one wall. Fig. 4 is a perspective view of the bag, showing 45 it closed or folded and presenting the outside handkerchief-pocket.

While material is not of the essence in my invention I prefer to form the bag throughout of leather.

50 A is the base or body of the device, in the

form of a rectangular sheet folded upon itself at its center, as at x, to afford the sides A' and A², which should be suitably stiffened to give permanent form to the bag, and from the opposite outer ends of which extend 55 the loop-handles r, r. A flap A³ extends from the edge of the side A', to cover the outside collapsible general pocket B, having a buckle q at which to fasten the flap by its tongue p. Inside the pocket B is a diaphragm or partition B², preferably of chamois-skin, in imitation of a lining and fastened, to the side A', about its edges, except the upper edge along which, at t, it is provided with an elastic band to maintain that edge taut and cause it to 60 hug the adjacent surface of the side A', thus to tend to secrete the pocket B' formed by the lining. In the outer side of the side A² is formed the diagonal pocket C, intended as a handkerchief-pocket; and on the inner surface of the side A' I provide the collapsible pockets D and D', intended, respectively, for 65 letters, postal-cards, and the like, and visiting-cards, and tickets.

Between the sides A' and A², the fold or 70 hinge x affords the compartment E, and is preferably wide enough to adapt the compartment to contain, without causing, thereby, the bag to bulge, a memorandum-book F, a reading-book or novel G, and a flat 75 lunch-box H, the latter to be loosely retained in the compartment; although the width of the compartment E need not be greater than will so accommodate the memorandum-book. In the fold or hinge x I provide means for 80 removably retaining in the compartment the book or books, and the means illustrated for this purpose comprise an endless elastic band o, one for each book, both passed through a pair of eyelets n, the members of which are 85 near the opposite ends of the fold x. Thus the book is held in the compartment by causing it to straddle or embrace between its leaves the inner length of an elastic band; while the retaining band obviously permits 90 the book to be readily withdrawn for use.

To fasten the sides A' and A² together, and thus close the bag, I show an elastic band m fastened at its ends to the side A' and adapted to be passed about the side A². 95

What I claim as new, and desire to secure by Letters Patent, is—

1. In a lady's hand-bag, the combination of the sides A' and A² having the connecting hinge α and forming a compartment E between them, fastening means in said compartment for removably securing a book therein, and a pocket B on one of said sides containing a partition-lining B² forming a secret pocket B' therein, substantially as described.

2. In a lady's hand-bag, the combination of the sides A' and A² having the connecting hinge α and affording a compartment E between them, fastening means in said compartment for removably securing a book therein, and a pocket B on one of said sides containing a partition-lining B² provided with an elastic band t extending along its free edge and forming a secret pocket B' therein, substantially as described.

3. In a lady's hand-bag, the combination of the sides A' and A² having the connecting hinge α and forming a compartment E between them, fastening means in said compartment for removably securing a book

therein, an outer pocket B on the side A' containing a partition-lining B² forming a secret pocket B' therein, a flap A³ for the said pockets, and inner pockets D and D' on the 30 said side A', substantially as described.

4. A lady's hand-bag comprising, in combination, the sides A' and A² provided with handles r and having the connecting hinge α and forming a compartment E between the 35 sides adequately wide to contain books F and G and a lunch-box H, fastening means in said compartment for removably securing the books therein, an outer collapsible pocket B on the side A' containing a partition-lining 40 B² forming a secret pocket B' therein, a flap A³ for the said pockets, provided with fastening means, inner collapsible pockets D and D' on the said side A', a diagonal outer pocket C on the side A² and a fastening-strap 45 m for the sides, substantially as and for the purpose set forth.

MARY E. HOYLE.
